S. M. LUCAS

RAILWAY TRAFFIC CONTROLLING APPARATUS

Filed August 27, 1923

INVENTOR:

S. M. Lucas,
by A. R. Venecell,
His Attorney.

UNITED STATES PATENT OFFICE.

SAMUEL M. LUCAS, OF PITTSBURGH, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed August 27, 1923. Serial No. 659,505.

My invention relates to railway traffic controlling apparatus of the type comprising train carried governing means controlled by energy in the trackway. More particularly 5 my invention relates to the trackway portion of such apparatus.

I will describe one form of railway traffic controlling apparatus comprising my invention, and will then point out the novel features 10 thereof in claims.

The accompanying drawing is a diagrammatic view showing one form and arrangement of trackway apparatus embodying my invention.

15 Referring to this drawing, the reference characters 1 and 1^a designate the track rails of a railway over which traffic normally moves in the direction indicated by the arrow. A track section A—C is separated from the rest of the track by means of insulated joints 2, and this section is further divided into sub-sections for purposes which will appear hereinafter. As here shown section A—C comprises a rear sub-section A—B 20 and a forward sub-section B—C, which sub-sections are separated by insulated joints 2^a.

Means are provided for supplying the rails of each sub-section in parallel with a train governing current which I will term 30 a "loop" current. For this purpose sub-section A—B is provided with an impedance 14 connected across the rails adjacent the entrance end of the sub-section and a similar impedance 15 connected across the rails adjacent the exit end of the sub-section. Two other similar impedances 16 and 17 are connected across the rails adjacent the entrance end and the exit end, respectively, of sub-section B—C. The connections of the loop 40 circuits are made to the mid points of these impedances.

Loop current is constantly supplied to sub-section A—B by a loop transformer E, the circuit passing from the secondary 10 of transformer E, through wire 22, impedance 15, the rails of sub-section A—B, impedance 14, and wire 23 back to transformer E. The primary 11 of transformer E is constantly supplied with alternating current from an alternator H, over line wires 5 and 5^a.

The sub-section B—C is at times supplied with loop current from a loop transformer D, the primary 9 of which is constantly supplied with alternating current from line

wires 5 and 5^a. The loop circuit for sub-section B—C passes from secondary 8 of loop transformer D, through wire 24, circuit controller F operated by a signal S^c, wire 25, impedance 17, through both rails of sub-section B—C in parallel, impedance 16, and 60 wire 26 back to transformer D. The circuit just traced is closed only when signal S^c indicates caution or proceed, and at all other times the supply of loop current to sub-section B—C is discontinued. 65

The purpose of the insulated joints 2^a at point B is to prevent the flow of loop current from one sub-section to the other.

Track circuit current of one relative polarity or the other is supplied to the entire 70 section A—C from a track transformer T, the primary 4 of which is constantly supplied with alternating current from line wires 5 and 5^a. Interposed between the secondary 3 of transformer T and the rails of 75 section A—C is a pole changer J controlled in any suitable manner as by signal S^c.

Track circuit current is carried past the insulated joints 2^a at point B by means of a bonding device K. As shown in the 80 drawing device K comprises a core 18 of magnetizable material such as laminated iron. This core is provided with a winding 19 connected around joint 2^a in rail 1, and a second winding 20 connected around 85 joint 2^a in rail 1^a. These windings are so arranged on the core 18 that the magnetic fields set up in this core by currents flowing in opposite directions in the two windings 19 and 20 at any instant tend to 90 neutralize each other and the impedance offered to track circuit current by the bonding device K is, therefore, very low. If, however, any loop current flows from sub-section B—C to sub-section A—B or vice 95 versa through device K, it passes through windings 19 and 20 in the same direction and the impedance of the bonding device K is therefore comparatively high and hence is effective to choke back such currents. It 100 is, therefore, plain that stray loop currents are prevented from passing from one sub-section to the other.

The trackway apparatus herein shown and described is intended for co-operation with 105 train carried governing mechanism so arranged that a less restrictive indication is received on the train when both track and

loop currents are present in the rails, and a more restrictive indication is received on the train when loop current is not present in the rails. Obviously, then, if loop current strays from one sub-section into another sub-section which is not supplied with loop current in the normal manner, a less restrictive indication will be given when a more restrictive indication should be given. One feature of my invention is the prevention of such stray supply of loop current, without interfering with the free flow of track circuit current from sub-section to sub-section.

15 Although I have herein shown and described only one form and arrangement of railway traffic controlling apparatus embodying my invention, it is understood that various changes and modifications may be made therein within the scope of the appended claims without departing from the spirit and scope of my invention.

Having thus described my invention, what I claim is:

- 25 1. Trackway apparatus for a train controlling system comprising a section of track divided into two sub-sections insulated from each other, means for supplying each sub-section separately with loop current which flows through the track rails in multiple, and means for supplying the two sub-sections in series with track circuit current which flows through the track rails in series.
- 30 2. Trackway apparatus for a train controlling system comprising a section of track divided into sub-sections, means for supplying each sub-section separately with loop current which flows through the track rails in multiple, means for supplying track circuit current which flows through the track rails in series to one said sub-section, and means for allowing the flow of track circuit current but not loop current from one said sub-section to the other.
- 35 3. In combination, a stretch of railway track divided into a forward and a rear sub-section, means for constantly supplying loop current to said rear sub-section, means responsive to traffic conditions for supplying loop current to said forward sub-section,

means for supplying track circuit current to said forward sub-section, and means for conducting said track circuit current but not loop current from said forward section to 55 said rear section.

4. In combination, a stretch of railway track divided by means of insulated joints into a forward and a rear sub-section, means for supplying each sub-section separately 60 with current which flows in the same direction in the two track rails, means for supplying an electromotive force across the rails of said forward sub-section, and a bonding device adjacent the junction of said 65 two sub-sections for permitting current flowing in opposite directions in the two rails but not current flowing in the same direction in the two track rails, to pass from one sub-section to the other. 70

5. In combination, a stretch of railway track divided by means of insulated joints into a forward and a rear sub-section, means for supplying each sub-section separately 75 with current which flows in the same direction in the two track rails, means for supplying an electromotive force across the rails of said forward sub-section, and a bonding device adjacent the junction of said two sub-sections and comprising a magnetizable core, a first winding on said core connected around the insulated joint in one rail, and a second winding on said core connected around the insulated joint in the other rail, the two windings being so disposed that the magnetic fields set up by currents flowing in opposite directions in the two windings at any instant tend to neutralize each other. 80

6. Trackway apparatus for a train controlling system comprising a section of track divided into sub-sections insulated from each other, means for supplying each sub-section separately with loop current which flows through the track rails in multiple, 90 and means for supplying the sub-sections in series with track circuit current which flows through the track rails in series. 95

In testimony whereof I affix my signature.

SAMUEL M. LUCAS.
